UNITED STATES PATENT OFFICE.

GEORGE R. GUILD, OF THE UNITED STATES ARMY, ASSIGNOR OF ONE-HALF TO
C. T. PAYTON, OF ST. LOUIS, MISSOURI.

SIGNALING DEVICE.

1,276,648.

Specification of Letters Patent. Patented Aug. 20, 1918.

Application filed October 13, 1917. Serial No. 196,416.

To all whom it may concern:

Be it known that I, GEORGE R. GUILD, a citizen of the United States and an officer of the United States Army, stationed at 5 Baltimore, Maryland, have invented a certain new and useful Improvement in Signaling Devices, of which the following is a full, clear, and exact description, such as will enable others skilled in the art to which 10 it appertains to make and use the same, reference being had to the accompanying drawings, forming part of this specification.

My invention relates to a signaling device particularly designed for use in connection with the signaling systems utilized for the control of railway trains, interurban railway cars, street cars, and the like, the principal object of my invention being 15 to provide a comparatively simple and efficient signaling device wherein the signal light is readily discernible throughout the daylight period as well as at night, such result being attained by means of a reflector 20 positioned within a housing and disposed a substantial distance to the rear of an opening in the wall of the housing, and a source of light arranged so that its rays are thrown directly onto said reflector.

30 A further object of my invention is to provide a signaling device, including a source of light, a lens, and a reflector, the same being combined and arranged within a suitable housing, so that the surface of 35 the reflector onto which the rays of light are transmitted by the lens, is readily discernible at a considerable distance away from the device, and likewise readily discernible from any point in front of the signaling device within comparatively wide vertical and horizontal angles.

My improved signaling device is primarily intended to take the place of the well-known bull's-eye or target signal devices now in general use in railway signaling systems and the like, and in this connection it will be understood that in practically all of these bull's-eye or target signals, a source of light is positioned directly 45 behind a lens, the latter being located in the wall of a housing and while such signaling devices are effective at night, they cannot be advantageously used during the 50 daylight period for the reason that the sun's rays or rays of light which may pass

through the lens and into the housing counteract the light rays from the lamp within said housing. Furthermore, the so-called target or bull's-eye signal lamps can only be observed from a position, or from points 60 within a limited area, directly in front of the lamp, and for this reason, such signal lamps cannot be used adjacent to those portions of a railway track containing comparatively sharp curves or on switches and 65 turnouts.

With the foregoing and other objects in view, my invention consists in certain novel features of construction and arrangement of parts hereinafter more fully described and 70 claimed, and illustrated in the accompanying drawings, in which—

Figure 1 is a vertical section taken through the center of a signaling device of 75 my improved construction;

Fig. 2 is a front elevational view of the housing containing my improved signaling device with a part thereof in section;

Figs. 3 and 4 are diagrammatic views illustrating the comparatively wide vertical and horizontal angles through which the reflector of my improved signaling device may be observed.

Referring by numerals to the accompanying drawings and particularly Figs. 1 and 85 2 which illustrate a practical embodiment of my invention, 10 designates a housing of any desired size and shape, and formed in the front wall thereof near the top is an opening 11. Arranged within the housing 90 directly behind the opening 11 is a frame 12 which carries on its front side a comparatively flat convex reflector 13. This frame and reflector normally occupy an angle of approximately forty-five degrees, 95 and this angular position can readily be adjusted by virtue of the fact that the top and bottom of frame 12 are provided with pivotally mounted buttons 14, the heads of which are arranged to slide freely between 100 suitable guides 15, the latter being applied to the top and rear wall of housing 10.

Mounted for sliding movement between guides 16 on the bottom of the housing is a standard 17 to which is pivotally connected 105 in any suitable manner an ear 18 which depends from a cup-shaped reflector 19. Removably positioned in the bottom of this cup-shaped reflector is a source of light, preferably an electric lamp 20, the same 110

having suitable connections to a lighting circuit.

Arranged for vertical adjustment on the inside of the front wall of the housing below opening 11 is a plate 21 to the upper end of which is hinged a short link 22, the upper end of the latter being in turn hinged to a frame 23. This frame occupies a position directly over the cup-shaped reflector 19, and its rear end is hinged to a plate 24, the latter being mounted for vertical adjustment upon the standard 25 which projects upwardly from the bottom of housing 10.

Adjustably positioned on frame 23 is a convex condensing lens 26, said frame and lens normally occupying a position at an angle of approximately twenty or, twenty-five degrees relative to a horizontal plane.

With the parts properly positioned and lamp 20 lighted, the rays therefrom are thrown upward by reflector 19 and said rays in passing through lens 26 are thereby condensed and thrown upwardly against the convex reflector 18.

By virtue of the fact that the reflector 18 is convex, the light rays thrown or reflected outwardly through opening 18 will be readily visible throughout a comparatively high and wide area in front of the signaling device, and as said reflector is positioned a short distance to the rear of opening 11, it is not subject to direct rays of light from the exterior of the housing, and consequently, light thrown onto the surface of the reflector will be visible during the daylight period for a considerable distance away from the device, particularly if the condensing lens 26 be colored either red or green, such colors being widely used in railway signaling systems.

A signaling device of my improved construction is comparatively simple, is very effective in throwing reflected light throughout a comparatively wide area in front of said device, and for this reason the signal is particularly applicable for use at points adjacent to railway track curves and likewise adjacent to switches and turnouts.

By the use of a convex reflecting surface and the peculiar arrangement of said surface with respect to the opening in the housing of the device, the signal is readily discernible throughout a relatively high and wide area and from a considerable distance during the daylight period as well as at night.

It will be readily understood that minor changes in the size, form and construction of the various parts of my improved signal-

ing device, can be made and substituted for those herein shown and described, without departing from the spirit of my invention, the scope of which is set forth in the appended claims.

I claim:

1. In a signaling device of the class described, a housing provided with an opening, a convex reflecting surface disposed within the housing behind said opening, a condensing lens arranged within the housing below said opening and reflecting surface, said convex reflecting surface and condensing lens being adjustably mounted within said housing, and a source of light below said lens.

2. In a signaling device of the class described, a housing provided with an opening, a convex reflecting surface disposed within the housing behind said opening, a condensing lens arranged within the housing below said opening and reflecting surface, a source of light below said lens, and a reflector for said source of light, said reflecting surface, condensing lens, and reflector being adjustably arranged within said housing.

3. In a signaling device of the class described, a source of light, a reflector therefor, a reflecting surface occupying an angular position adjacent to said source of light and the reflector therefor, and a lens interposed between said source of light and reflecting surface, said reflector, reflecting surface and lens being independently adjustable.

4. In a signaling device of the class described, a housing provided with an opening, an adjustably mounted reflecting surface occupying an angular position within the housing to the rear of said opening, a source of light within the housing below the opening therein, an adjustable reflector for said source of light, and an adjustably mounted lens interposed between the source of light and the adjustable reflecting surface.

5. In a signaling device of the class described, a housing provided with an opening, a reflecting surface disposed within the housing behind said opening, a source of light within the housing below the reflecting surface, and an adjustably mounted lens positioned between the source of light and the reflecting surface.

In testimony whereof I hereunto affix my signature this 3rd day of October, 1917.

GEORGE R. GUILD.
